UNITED STATES PATENT OFFICE.

ROY A. FISK, OF AMBOY, MINNESOTA.

HEATING DEVICE FOR WATER-JACKETED CARBURETERS.

1,216,301.

Specification of Letters Patent. Patented Feb. 20, 1917.

Application filed June 1, 1916. Serial No. 101,134.

To all whom it may concern:

Be it known that I, ROY A. FISK, a citizen of the United States, residing at Amboy, in the county of Blue Earth, State of Minnesota, have invented certain new and useful Improvements in Heating Devices for Water-Jacketed Carbureters; and I do hereby declare the following to be a full, clear, and exact description of the invention, such as will enable others skilled in the art to which it appertains to make and use the same.

This invention relates to carbureters and has special reference to a heating device for water jacketed carbureters.

One important object of the invention is to provide means whereby the water of a water jacketed carbureter may be heated, the means being of improved character so that the hydro-carbon in the carbureter will be vaporized and the entering air warmed whereby the compression will be greater, the engine will fire quicker, and consequently there will be produced a greater mileage to the given quantity of the hydro-carbon.

A second important object of the invention is to provide a device of this description wherein the water in the water jacket will be kept in proper circulation during the operation of the engine.

With the above and other objects in view, as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:

Figure 1 is a side elevation of a carbureter with the water jacket and other connected parts shown in section;

Fig. 2 is a plan view thereof;

Fig. 3 is a section on the line 3—3 of Fig. 2, the carbureter body proper being shown in elevation.

In the present embodiment of the invention, the invention has been shown as applied to the carbureter which is commonly known as a "Rayfield carbureter" and the body of such a carbureter is indicated at 10. Surrounding this body 10 is a wall 11 so that between the body and the wall is formed a water jacket 13. At 14 is a cylindrical

receptacle which constitutes a water heating chamber and the upper end of this receptacle is closed by a plug 15 supporting an insulating sleeve 16 through which passes the electric wires 17, the wires being preferably connected to a storage battery of suitable voltage. Depending from the plug 15 is the heating element which consists of a tube 18 closed at its bottom and carrying within it a resistance coil 19. The lower end of this receptacle 14 is connected to the bottom of the water jacket by means of a passage 20 while the upper end of the water jacket is connected to the upper part of the receptacle 14 by a tubular connection 21. The connection 20 has depending therefrom a pet-cock 22 for the purpose of drawing off the contents of the water jacket and receptacle 14 when desired and also the water jacket is provided with an overflow pet-cock 23.

At 24 is a filling tube which is connected to the water jacket by a bend 25 and which is normally closed by a plug 26. This filling tube is provided with an overflow valve 27 at one side.

In the operation of the device, when it is desired to start the carbureter the water jacket is preferably filled with hot water. Then, the carbureter may be started readily with the hydro-carbon vaporized properly. After being started, the current is turned on the wires 17 by means of a switch located on the dash of an automobile and the water in the receptacle 14 heated. As the water is heated, there is established a circulation upwardly of the receptacle 14 and thence through the connection 21 to the body of the water jacket 13. This action will ultimately heat the entire body of water in the jacket 13 by reason of the cross currents that will naturally be established under the influence of the discharge into the body 13 through the passage 21 and the oppositely directed flow through the connection 20.

There has thus been provided a simple and efficient device of the kind described and for the purpose specified.

It is obvious that many minor changes may be made in the form and construction of the invention without departing from the material principles thereof. It is not therefore desired to confine the invention to the exact form herein shown and described but it is wished to include all such as properly come within the scope claimed.

Having thus described the invention what is claimed as new, is:—

1. The combination with a carbureter having a float chamber; of a water jacket surrounding the float chamber, a heating chamber having its lower end connected to the lower end of the water jacket, a heating element in the heating chamber and a tubular connection between the upper parts of the water jacket and heating chamber.
2. The combination with a carbureter having a float chamber; of a water jacket surrounding the float chamber, a heating chamber having its lower end connected to the

lower end of the water jacket, a heating element in the heating chamber consisting of a tube extending into the chamber and having a closed lower end, and a resistance coil in said tube, and a tubular connection between the upper parts of the water jacket and heating chamber.

In testimony whereof, I affix my signature, in the presence of two witnesses.

ROY A. FISK.
